HIS ATTORNEY.

UNITED STATES PATENT OFFICE

ALFRED A. HENTZELL, OF LITTLETON, COLORADO, ASSIGNOR TO INGERSOLL-RAND COMPANY, OF JERSEY CITY, NEW JERSEY, A CORPORATION OF NEW JERSEY

FORGING MECHANISM

Application filed July 23, 1931. Serial No. 552,582.

This invention relates to forging mechanism, but more particularly to forming dies for forging mechanism of the type used for sharpening working implements, such as drill steels and the like.

One object of the invention is to enable the forming dies to be readily adjusted for the accommodation of drill bits of different sizes.

Another object is to assure the correct construction of the cutting bit, and still another object is to simultaneously effect the adjustment of the forging dies both for raising and lowering the dies and also to adjust the dies laterally with respect to each other.

15 Other objects will be in part obvious and in part pointed out hereinafter.

In the drawings illustrating several forms which the invention may assume in practice and in which similar reference characters refer to similar parts,

20 Figure 1 is a sectional elevation of a pair of co-acting forming dies constructed in accordance with the practice of the invention,

Figure 2 is a plan view of the bottom die assembly taken through Figure 1 on the line 2—2 looking in the direction indicated by the arrows,

25 Figure 3 is an end view of a lower die assembly, partly broken away,

30 Figure 4 is a sectional elevation of a modified form of co-acting forming dies,

Figure 5 is a plan view of the bottom die assembly taken through Figure 4 on the line 5—5 looking in the direction of the arrows,

35 and

Figure 6 is an end view of the bottom die assembly shown in Figure 4.

Referring more particularly to the drawings, and at first to the form of the invention illustrated in Figures 1 to 3 inclusive, A designates a stationary die holder which may be an integral portion of a drill sharpener or like apparatus used for forging the cutting bits on working implements, such as the drill steel

45 designated by B and only the bit end of which is indicated. C represents a die holder disposed above the die holder A and which may be reciprocable relatively to the die holder A as is customary in mechanism of this type.

50 In the adjacent surfaces of the die holders

A and C are seating surfaces D and E respectively on which are seated co-acting forming die assemblies F and G. The die assemblies are similar in all their essential respects and are clamped against surfaces H in the die 55 holders A and C by plates J seated against the ends of the die holders and clamped firmly against the die assemblies by means of bolts K threaded into the die holders.

Each die assembly, constructed in accordance with the practice of the invention, comprises a base member L having a plain bottom surface O which, in the assembled position of the die assembly in the die holder, seats against the seating surfaces, either D 60 or E in the die holders.

In the upper surface of the base member L is a central groove P which extends longitudinally through the base member and said groove P should be of a width to accommodate drill bit wings, such as those designated by Q, of the maximum thickness which the die assembly is intended to accommodate. On the opposite sides of the groove P and in the upper surface of the base member L are 70 longitudinally extending grooves R and R' which extend through the entire length of the base member and have surfaces S and T arranged at right angles to each other and preferably inclined at 45° angles with respect to the surface O of the member L.

75 Seated in the grooves R and R' are blocks U and V respectively which constitute dies whereby the drill bit wings Q may be shaped. The forming dies U and V differ from each other only in that they are of opposite hand and each die is provided on its lower surface with a longitudinally extending projection or rib W shaped to conform to the grooves R and R'. The ribs W accordingly have 80 angularly arranged surfaces X and Y adapted to seat upon the surfaces S and T of the base member L.

85 The inner or adjacent surfaces Z of each pair of dies are suitably spaced with respect to each other to form therebetween a slot b into which metal may flow when the upper die holder C descends upon the work. The upper surfaces e of the dies are perpendicular to the surfaces Z and are flat to shape the 90

100

side surfaces of the wings Q of the drill bit. Preferably the surfaces c constitute the bottom surface of a depression or recess d formed in the contiguous surfaces of opposing 5 pair of dies, and at the inner end of the surface c is an inclined surface e which may serve to form the correct angularity of the cutting edge of the bit.

In order to enable the dies U and V to be 10 conveniently adjusted, both laterally with respect to each other and to be raised or lowered to assure the proper wing thickness, shims f are disposed between the surfaces Y of the dies and the surfaces T of the 15 base member L and screws g bearing in the base member L are threaded into the die blocks U and V to clamp the said die blocks securely in position. The screws g are arranged in parallelism with respect to the 20 inner seating surfaces S and may therefore exert a suitable clamping pressure on the die blocks irrespective of the thickness of the shims f which may be placed between the die blocks and the base member.

To the end that the die assemblies may be 25 conveniently held within the die holders by the mere application of clamping pressure against the base member L, said base member is provided with a tapered surface h at its 30 rear end to seat against a correspondingly tapered surface i on lateral projections k at the rear ends of the die blocks U and V. The projection k of the die blocks thus seat against the surfaces H of the die holders and 35 are pressed thereagainst through the medium of the base member against the outer end of which is clamped the plate J.

Arranged in the manner described, the die 40 blocks may be readily raised or lowered and simultaneously adjusted laterally with respect to each other to assure the formation of drill bit wings of different thickness by merely inserting shims f of the proper thickness between the die blocks and the base member, or by removing a shim or shims to 45 lower the die blocks with respect to the base member and by so doing to also spread the die blocks apart in order that drill bits having wings of greater width may be formed.

In the modified form of the invention illustrated in Figures 4 to 6 inclusive the lower and upper die assemblies designated by o and p respectively are secured on the surfaces D and E of the die holders A and C by plates 50 q clamped to the front ends of the die holders by the screws K.

Each die assembly o and p comprises a base member r which seats upon the seating surface D of the die holder and has an upper tapered surface s which declines from the front end of said base member to support die blocks t and u. The die blocks are provided with tapered surfaces v to correspond to the taper of the surfaces s upon which they seat, 55 and in said tapered surfaces v are formed

dove-tail grooves w to accommodate correspondingly shaped ribs x on the tapered surfaces s of the base members r.

The grooves w, and therefore the ribs x, incline with the degree of inclination of the surfaces s and v and also diverge from the high or outer end of the base member r and preferably extend throughout the length of said base member.

The base member r is of somewhat shorter length than the seating surface upon which it seats, either D or E, so that it may be conveniently actuated longitudinally of the said seating surfaces. The means provided for such actuation of the base member r comprises in this instance a screw y which is threaded into a threaded aperture z in the base member and is provided with a cylindrical portion 2 journaled in a slot 3 in the plate q. At the juncture of the cylindrical portion 2 and the threaded portion of the screw is a collar 4 which seats against the inner face of the plate q to prevent endwise movement of the screw in an outwardly direction with respect to the plate. At the outer end of the screw y is the usual head 5 which seats against the outer surface of the plate and whereby the screw may be manipulated.

In practice, whenever it is desired to adjust the die blocks, both as to elevation and laterally with respect to each other, it is merely necessary to reduce the clamping pressure of the plate q acting against the outer ends of the die blocks and whereby said die blocks are clamped firmly against the surfaces H of the die holders. The screw y may then be rotated, either to draw the base member r towards the plate q or to advance it in the direction of the surfaces H. By thus actuating the base member r the die blocks may be raised or lowered to suitably space the opposing pairs of dies for assuring the proper wing thickness of the drill bit and, simultaneously with such adjustment, the dies of a pair will be spread or drawn together. After the die blocks have been properly adjusted, the screw K may again be manipulated to clamp the plate q firmly against the die blocks. The entire assembly 100 will then be held in the correct position for long periods of operation and the relative positions of the parts will remain unaffected by the severity of the jars to which apparatus of this character is generally subjected.

I claim:

1. In forging mechanism, the combination of coacting die holders relatively movable toward and from each other and having seats in their opposing faces, base members on the seats, a pair of forming dies on each base member, and means for adjusting the dies on one base member laterally of the dies on another base member and for effecting relative lateral adjustment of the dies of a pair.

2. In forging mechanism, the combination of coacting die holders relatively movable toward and from each other and having seats in their opposing faces, base members 5 on the seats and having guide elements, a pair of forming dies on each base member and being interlocked with the guide elements, and means for adjusting one pair of dies laterally of another pair of dies for 10 simultaneously effecting lateral adjustment of the dies of a pair.
3. In forging mechanism, the combination of coacting die holders relatively movable toward and from each other and having seats 15 in their opposing faces, base members on the seats and having guide elements, a pair of forming dies on each base member and being interlocked with the guide elements, and means for effecting relative adjustment between the dies of a pair and between each 20 pair of dies and the associated base member.
4. In forging mechanism, the combination of coacting die holders relatively movable toward and from each other and having seats 25 in their opposing faces, base members on the seats, a pair of forming dies on each base member, and means for adjusting each die in a plane perpendicular to its die holder and to simultaneously adjust the said die in a plane 30 paralleling the die holder.
5. In forging mechanism, the combination of coacting die holders relatively movable toward and from each other and having seats 35 in their opposing faces, base members on the seats, forming dies supported by the base members, and means for adjusting the dies relatively to the base members and for simultaneously effecting relative lateral adjustment 40 of the dies associated with each base member.
6. In forging mechanism, the combination of coacting die holders relatively movable toward and from each other and having seats in their opposing faces, base members on the 45 seats having grooves therein, pairs of forming dies supported by each base member and being seated in the grooves, and shims in the grooves to effect adjustment of the dies of a pair relatively to each other and relatively to the base member whereby they are supported. 50
7. In forging mechanism, the combination of coacting die holders relatively movable toward and from each other and having seats 55 in their opposing faces, base members on the seats having grooves therein, said grooves having seating surfaces inclined with respect to each other and with respect to the seats, forming dies arranged in pairs on each base 60 member and being seated in the grooves, and shims in the grooves to effect adjustment of the dies of a pair relatively to each other and relatively to the base member whereby they are supported. 65
8. In forging mechanism, the combination 70 of coacting die holders relatively movable toward and from each other and having seats in their opposing faces, base members on the seats, a pair of forming dies seated on each base member, and manually operable means for actuating the base members to simultaneously adjust the dies of a pair laterally with respect to each other.
9. In forging mechanism, the combination 75 of coacting die holders relatively movable toward and from each other and having seats in their opposing faces, base members on the seats having inclined surfaces, a pair of forming dies on each base member and having inclined surfaces seating upon the inclined surfaces of the base members, interlocking slideable connections between each base member and the dies of a pair and being arranged diagonally with respect to the base members, and means for actuating the base members 80 to raise and lower the dies with respect to the seats and for adjusting the dies laterally with respect to each other.
10. In forging mechanism, the combination 85 of coacting die holders relatively movable toward and from each other and having seats in their opposing faces, base members on the seats having inclined surfaces, forming dies arranged in pairs on the base members and having diagonal grooves therein, projections on the inclined surfaces extending into the grooves and means for actuating the base members longitudinally of the dies to raise and lower the dies with respect to the seats 90 and to adjust the dies laterally with respect to each other.
11. In forging mechanism, the combination 95 of coacting die holders relatively movable toward and from each other and having seats in their opposing faces, base members on the seats having forming dies arranged in pairs on the base members, said base members and dies having cooperating inclined surfaces, said dies having diagonal grooves in their inclined surfaces, diagonal ribs on the base members extending into the grooves and being slidably interlocked therewith, means for clamping the dies to the die holders, and screw means acting against the said means 100 and being threaded into the base members to actuate the said base members longitudinally of the die for elevating and lowering the dies and for simultaneously adjusting the dies laterally with respect to each other. 105

CERTIFICATE OF CORRECTION.

Patent No. 1,896,621 .

February 7, 1933.

ALFRED A. HENTZELL.

It is hereby certified that error appears in the printed specification of the above numbered patent requiring correction as follows: Page 3, line 9, claim 2, after "dies" second occurrence insert the word "and", and line 10, after "effec-
ting" insert the word "relative"; same page, line 23, claim 4, for "coating" read
"coating"; and that the said Letters Patent should be read with these corrections
therein that the same may conform to the record of the case in the Patent Office.

Signed and sealed this 14th day of March, A. D. 1933.

M. J. Moore,

Acting Commissioner of Patents.
